UNITED STATES PATENT OFFICE.

LAWRENCE A. ABBOTT, OF CHICAGO, ILLINOIS.

GAS-MOTOR.

1,126,332.

Specification of Letters Patent. Patented Jan. 26, 1915.

Application filed April 7, 1913. Serial No. 759,451.

To all whom it may concern:

Be it known that I, LAWRENCE A. ABBOTT, a citizen of the United States, residing at Chicago, in the county of Cook and State of Illinois, have invented certain new and useful Improvements in Gas-Motors, of which the following is a specification.

The present invention relates more particularly to that style of gas motor known 10 as two cycle.

One of the objects of the invention is to employ an upper piston and a lower piston, and to arrange the connections between said pistons and the crank shaft so as to minimize the strain exerted upon the crank shaft 15 when the explosive charge is fired.

A further object of the invention is to provide means for admitting a fresh charge of explosive mixture to a point between the two 20 pistons, and a further object is to provide means for exhausting the burned gases from between the pistons, and to utilize the pressure of the fresh explosive charge as a means for forcing the burned gases out through 25 the exhaust port.

The invention further consists in the features of construction and combination of parts hereinafter described and claimed.

In the drawings: Figure 1 is a view partly 30 in section, and of a semi-diagrammatical nature, showing the position of the pistons and the position of the connecting rods between the pistons and crank shaft at, or approximately at, the commencement of the 35 driving stroke; Fig. 2 a view similar to Fig. 1 showing the position of the parts after the crank has been turned a quarter revolution; Fig. 3 a view similar to Fig. 1 showing the position of the parts when the crank has 40 turned a half revolution; Fig. 4 a view similar to Fig. 1 showing the position of the parts when the crank has been turned a three quarter revolution; Fig. 5 a vertical section of the engine of the present invention; 45 Fig. 6 a section on line 6—6 of Fig. 4 looking in the direction of the arrow; Fig. 7 a section on line 7—7 of Fig. 4 looking in the direction of the arrow; and Fig. 8 a curve chart showing the movements of the two 50 pistons, and showing the relation between the pistons at the time of opening and closing the exhaust and opening and closing the intake.

The present invention, as heretofore 55 stated, relates more particularly to that type of gas motor known as the two cycle; that

is one in which a fresh explosive mixture is drawn in and fired upon each complete revolution of the crank shaft.

The present invention utilizes two pistons, an upper one and a lower one and arranges the connections between these pistons and the crank shaft so that when the explosive mixture is fired one of the pistons will push upon the crank shaft and the other 60 pull, the force of both of the pistons being exerted toward moving the crank shaft in a common direction, but the combined push and pull will equalize the strain to which the crank shaft would be otherwise subjected to, 65 and thus eliminate at least to all practical purposes, the wear and tear incidental to the strain placed on the crank shaft by the violent impetus given to the pistons when the explosive mixture is fired.

Referring now to the drawings, and more particularly to Fig. 5, in which the structure is illustrated more in detail, the motor as illustrated, comprises a cylinder or casing 8, which if desired, may be extended so as to 70 form a housing or casing 9 for the crank, although this portion of the structure may be varied in accordance with the ideas of the builder. The casing is also formed so as to provide a water chamber 10 for cooling 75 purposes, and attached to the upper end of the casing is a mixture box 11 provided with an air inlet 12, into which box enters a vapor supply pipe 13. The combining of air and vapor to produce the explosive mixture 80 takes place within this box. Communication between the upper end of the cylinder and this box is controlled by means of a valve 14, opening downwardly, and maintained in normal seated position through the 85 instrumentalities of a spring 15, and the upper end of the cylinder is enlarged, as for instance by providing a series of grooves 90 16, the purpose of which will be more clearly hereinafter explained.

Moving within the cylinder 8 is an upper piston 17 and a lower piston 18. The upper piston, as illustrated, comprises a head 19 from which depends a tubular sleeve like member 20, and the lower piston 18 is arranged to travel within said sleeve 20 so that this second piston finds its bearing within the chambered portion of the upper piston. The upper piston is provided with a connecting rod 21 depending from the lower 110 portion of the sleeve 20, and this rod is connected to the crank shaft as at 22. The

lower piston is provided with a connecting rod 23 which is connected to the shaft as at 24. By referring to Figs. 1 to 5 inclusive it will be seen that these connections are 5 spaced apart approximately one quarter of the distance of the circle described by a revolution of the crank shaft, and that at the time of firing, or near the time of firing, the upper piston is at its lowermost position and the lower piston midway between 10 its highest and lowest positions.

Now taking the parts in the position shown in Fig. 1 or 5 and supposing the circuit is established at this time which creates the spark that fires the explosive mixture. The first quarter movement of the crank shaft moves the parts from the position shown in Fig. 1 into the position shown in Fig. 2, and assuming the lower end of 15 the connecting rod 23 of the lower piston to be at A, and the connecting rod 21 of the upper piston to be at B at the commencement of the stroke, the first quarter movement will move the lower end of the connecting rod of the upper piston from B to 20 C, and the lower end of the connecting rod of the lower piston from A to B. The connecting rod 21 of the upper piston when moved from B to C will exert a pull upon 25 the crank and the connecting rod 23 of the lower piston moving from A to B will exert a push on the crank. This combined push and pull communicated to the crank shaft upon the firing of the explosive mixture, 30 will serve to minimize the effect of the shock and jolt which would otherwise be communicated to the crank shaft upon the initial movement of the driving parts of the motor, after the explosion has taken place. 35

40 By comparing Figs. 1 and 2 it will be seen that upon this initial movement the upper piston will travel upward and the lower piston downward as would be natural in case of a sudden expansion of gas between the 45 pistons.

Now referring to Fig. 3 where the next movement of the parts is illustrated it will be seen that the connecting rod 21 is moved from the point C to the point D and 50 the connecting rod 23 has moved from the point B to the point C and by referring to the curve illustrating the relative movements of the pistons it will be observed that during this stroke the upper 55 piston will travel at an increased speed to the lower piston. In the movement from the position shown in Fig. 2 to that shown in Fig. 3, the pistons are traveling in the same direction, both of them being on their 60 upstroke, but as heretofore explained the upper piston during such movement is traveling at an increased speed to the lower piston.

Now referring to Fig. 4 in which the next 65 position of the parts is illustrated when the

crank shaft has been turned a three quarter revolution, it will be seen that the connecting rod 21 will have traveled from the point D to the point A, and that the connecting rod 23 will have traveled from the point C 70 to the point D. During this movement the pistons will again travel in opposite directions, the upper piston downward and the lower piston upward, with the lower piston traveling at an increased speed. The foregoing describes the various positions assumed by the parts during a quarter, half, and three quarters revolution of the crank shaft. To obtain the final quarter of the revolution the connecting rod 21 is moved from 80 A to B, and connecting rod 23 from D to A bringing the parts back to the position shown in Fig. 1.

The upper piston 17 is provided with a cross passage 25 which is formed, in the 85 construction shown, by making the piston of two pieces, joining the same together, and spacing them apart by means of washers 26, but of course this precise construction may be varied. Communication between the cross passage and the under face of the piston is controlled by a check valve 27, opening downward, and normally held in seated position by a spring 28, this may be termed the intake for the explosive mixture. In the construction illustrated the casing is provided with a chamber 29 from which leads an exhaust pipe 30, and the sleeve 20 of the upper piston is provided with a series of ports or openings 31. These 90 ports serve to establish communication between the chamber 29 and the space between the pistons 17 and 18 when the burned gases are exhausted.

The operation of admitting the fresh explosive mixture and exhausting the burned gases will now be explained. When the parts move from the position shown in Fig. 1 to the position shown in Fig. 2 it will be understood that by reason of the travel of 110 the pistons in opposite directions the ports 31 will be brought above the top of the lower piston 18 and communication thus established between the space between the piston and the discharge chamber 29. Still referring to Fig. 2 it will be noted that the passage 25 has not yet been brought into communication with the grooves 16 and so the fresh charge of explosive mixture has not yet been admitted between the pistons, 115 but the upper piston upon its down stroke has opened the valve 14 and sucked in a fresh supply of mixture which is lying above the upper piston, and upon the upward stroke of the upper piston the valve 14 has been closed, and the explosive charge 120 previously admitted is being compressed between the upper face of the upper piston and the top of the cylinder. Shortly after communication between the ports 31 and 130

the discharge chamber 29 is established, the cross passage 25 is brought into communication with the grooves 16 and the compressed fresh mixture will flow through this cross passage, unseating the valve 27, and entering into the space between the pistons. The action of this mixture entering under pressure will force the burned gases out through the discharge passage. By referring to Figs. 2 and 3 it will be seen that both the lower piston and the upper piston will be traveling upward, during a quarter revolution of the crank shaft which moves the parts from the position shown in Fig. 2 to the position shown in Fig. 3, and during this quarter revolution of the crank shaft communication will be constantly established between the space between the pistons and the exhaust passage, and furthermore, during this stroke, the fresh explosive mixture will be constantly entering the space between the pistons under pressure, and will force the burned gases out through said discharge passage. During the next stroke which moves the parts from the position shown in Fig. 3 to that shown in Fig. 4 the pistons will move in opposite directions, the upper piston downward and the lower piston upward. At the commencement of this stroke the lower piston will operate to close communication between the spaces between the pistons and the exhaust passage by reason of its passing over and blocking communication through the ports 31, so that during this stroke the fresh explosive charge will be compressed between the pistons, when the fresh charge between the pistons has been compressed to a point to create a pressure stronger than the pressure of the fresh mixture above the upper piston, the valve 27 will close, and a further inlet of explosive mixture between the pistons prevented. At some time during this movement of the pistons in opposite direction, either when the pistons are at their closest relative position, or at some period during the final quarter movement of the crank shaft, the charge will be fired so that the expansion of the highly compressed mixture will give the maximum efficiency or power to the subsequent stroke.

It is believed that the operation of the parts will be understood from the foregoing, and especially so in view of the following explanation of the curve chart: Assuming that the line 32 on said chart represents the different positions of the lower piston 18, the line 33 represents the different positions of the upper piston; the line 34 represents the different positions of the ports 31; the line 35 represents the different positions of the passage 25; the line 36 represents the grooves 16 and the line 37 represents the exhaust chamber 29. Then upon movement of the parts from the posi-

tion shown in Fig. 1 to that shown in Fig. 2 the upper edge of the upper piston 17 will have moved to the point 38, and the upper edge of the lower piston 18 will have moved to the point 39. The ports 31 will have registered with the exhaust chamber 29 at the point 40, and the lower piston will have moved downward and the upper piston upward a sufficient distance to establish communication between the ports 31 and the exhaust chamber 29, said communication being first established at the point 41. The passage 25 will be brought into communication with the groove 16 at the point 42, and it will thus be seen that the exhaust is open a short time before the intake.

In traveling from the position shown in Fig. 3 the upper piston will have traveled from the point 38 to the point 43, and the lower piston from the point 39 to the point 44, both traveling in the same general direction, although the upper piston is traveling at a somewhat increased speed. The point 45 represents the point at which the lower cylinder acts to close the ports 31, and the point 46 indicates the point where the passage 25 is brought out of communication with the groove 16, cutting off the intake of fresh fuel. From this it will be seen that the exhaust closes before the intake.

In traveling from the position shown in Fig. 3 to that shown in Fig. 4 the upper piston will travel from the point 43 to the point 47, and the lower piston will travel from the point 44 to the point 48, both pistons traveling in opposite directions and compressing the fresh mixture between the pistons. Then in traveling from the position shown in Fig. 4 back to the position shown in Fig. 1 the upper piston will travel from the point 47 to the point 49, and the lower piston from the point 48 to the point 50, and at some time during this movement the fresh charge is fired. It would be advisable to fire the charge at about the time when the upper piston has reached the point 51 and the lower piston the point 52, at which time the pistons are in closest position to one another, and the greatest compression of the mixture is obtained, the particular time of firing, however, can be arranged according to the desire of the manufacturer or operator, but should be during the period of movement of the parts from the position shown in Fig. 4 to that shown in Fig. 1.

By referring to the drawings it will be seen that the points of engagement between the connecting rod and the crank shaft are spaced apart approximately a quarter of the distance of the circle described by the crank shaft during a revolution. As illustrated in the drawings, the connecting rods are eccentrically attached to a series of disks

53, but of course a crank shaft of other suitable formation may be used in place thereof, by utilizing the disks, however, the element of a fly wheel is provided for without using 5 a separate member for this purpose.

Referring now to Fig. 5 it will be seen that the connecting rod 23 is at its greatest angularity with respect to the pistons and that the connecting rod 21 is at a position 10 of approximate parallelism with respect to the pistons. I am of the opinion that if the impetus is given to the connecting rod when said rod is at the point of greatest angularity with respect to the piston, a 15 greater power will be transmitted to the crank shaft. Then when such impetus is given to the connecting rod when it is in a position of parallelism or approximately so with the pistons. Thus as the connecting 20 rod 23 descends, the degree of angularity between this rod and the pistons will be reduced, and as the connecting rod 21 moves upward, the angularity of this rod with respect to the pistons will be increased, so 25 the power transmitted through the medium of the connecting rod 23 decreases, the power transmitted through the medium of the connecting rod 21 increases during the first quarter movement and thus full power 30 is obtained by the combined movements of the two connecting rods in the manner above described. This fact will also be true in each quarter of a stroke, although as to whether the rod 21 for instance would decrease or 35 increase as the stroke progressed, would depend on the position of the pistons, but the

fact remains that on each quarter stroke, one of the rods increases its angularity thus maintaining power throughout.

A spark plug 54 is shown in the drawings which, when suitably connected constitutes an ordinary jump spark firing mechanism, and is operated at suitable intervals, in the ordinary and well known manner, to fire the explosive charge. 40

45 I claim:

In a gas motor, the combination of a cylinder, an outer hollow piston within said cylinder, an inner piston traveling within the chambered portion of said outer piston, 50 a crank shaft, a link connecting the outer piston and crank shaft, a link connecting the inner piston and crank shaft, the points of connection of the links with the crank shaft being a distance apart equal to a quarter revolution of said shaft, a valve inlet at the top of said outer piston for the admission of an explosive charge to the space between the pistons, an exhaust for the burnt gases controlled by the relative 55 positions of said pistons, means for firing the explosive charge admitted between the pistons while the pistons are in close proximity and the charge under compression, and said explosion occurring when the crank shaft has reached or approximately reached 60 the end of its first quarter strokes. 65
